(57) **CLAIM**

The ornamental design for a toy gun, as shown and described.

DESCRIPTION

FIG. 1 is a front perspective view of a toy gun, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1; and, FIG. 10 is an enlarged detail view of area 10 in FIG. 1.

The evenly broken lines in the drawings illustrate portions of the toy gun, which form no part of the claimed design. The dash-dot-dot broken lines encircling the enlarged views at FIGS. 1 and 9–10 are shown for the purpose of illustrating the bounds of the enlargement and form no part of the claimed design.
